FOUR-ELECTRODE TUBE

Henry Joseph Round, Westfield, Muswell Hill, London, England, assignor to Radio Corporation of America, a corporation of Delaware

Application June 16, 1927, Serial No. 199,170, and in Great Britain July 22, 1926

3 Claims. (Cl. 250—27.5)

This invention relates to four-electrode tubes, and more particularly to four-electrode tubes of the kind in which there is provided an outer grid acting as an electrostatic shield between an inner 5 grid and a plate.

The present invention has for its object the provision of a tube of the kind referred to, which shall be simple to construct and which shall be constructionally similar to as great a degree as 10 possible, to the well known three-electrode tubes of the type in which there is provided a filament, a grid substantially surrounding the filament, and a plate substantially surrounding the grid.

Briefly and broadly the object of this invention 15 is to provide a four-electrode tube comprising a filament, an inner grid substantially surrounding the filament, an outer grid electrode substantially surrounding the inner grid, and one or more plate electrodes, said outer grid electrode being formed 20 of a plate-like electrode having one or more windows filled with grid mesh parallel wires or the like therein, and said plate electrode or electrodes being located substantially opposite the said window or windows.

25 Preferably the plate electrode or electrodes is or are each slightly smaller than its appropriate window in the outer grid electrode, and is or are supported from the support rods for the outer grid electrode, being, of course, insulated therefrom.

The lead from the plate electrode or electrodes is passed through the bulb of the tube, the usual four-pin base and connection and supporting arrangements being employed for the remaining 35 electrodes. This arrangement of leads has the considerable advantage that the lead from the plate or plates is comparatively far removed from the other leads, so that the electrostatic coupling between the input and output circuits of the valve 40 is reduced to a very small value.

These and other advantages and objects of the invention will become more apparent, from the specification when read in connection with the herewith appended drawing on which:

45 Fig. 1 is an elevation of a tube constructed in accordance with my invention, and

Fig. 2 is a plan view of the tube shown in Fig. 1.

Referring to this drawing, 1 is a hair-pin filament supported upon leads 2 and a filament support 3. 4 is an inner grid carried upon supports 5. 6 is an outer grid electrode formed of a plate-like electrode, having a pair of oppositely disposed windows 7, cut in its flat sides, the said windows being filled with grid mesh parallel wires, cross wires or the like. The electrode 6 is

carried by support rods 8. 9, are plates smaller in area than the windows 7 and carried by means of yokes 10, supported on and insulated from the support rods 8 by means of glass beads 11. The lead 12 from the plates 9 is passed through the 60 side of the bulb 13 of the tube, the connections for the other electrodes being passed through the stem 14 to a four-pin base (not shown) in the usual way.

Having now particularly described and illustrated the nature of my said invention and in what manner the same is to be performed, what I claim is:

1. A thermionic valve comprising a filament, an inner grid surrounding the filament, an outer 70 grid electrode surrounding the inner grid, and plate electrodes, said outer grid electrode being formed of a plate-like electrode having windows filled with grid mesh parallel wires, and said plate electrodes being located opposite to the said windows.

2. A thermionic valve comprising a filament, an inner grid surrounding the filament, an outer grid electrode surrounding the inner grid, and a plate electrode, said outer grid electrode being 80 formed of a plate-like electrode having a window filled with grid mesh, and said plate electrode being smaller than the window and located opposite thereto.

3. An electron discharge device comprising a 85 cathode, an inner flattened cylindrical grid electrode surrounding the cathode, an outer flattened cylindrical grid electrode surrounding the inner grid electrode, the flattened portions of the outer grid electrode being provided with openings covered with grid mesh material, and a pair of plate electrodes external to and parallelly-arranged with respect to said grid meshed openings.

HENRY JOSEPH ROUND.
